MANUFACTURE OF SHOES

Charles F. Pym, Beverly, Mass., assignor, by mesne assignments, to The Littleway Process Company, Boston, Mass., a corporation of Massachusetts

Application January 12, 1929, Serial No. 332,156

35 Claims. (Cl. 12—145)

This invention relates to the manufacture of shoes. In some of its important aspects it involves special advantages as applied to the manufacture of shoes of that type in which an outsole is secured directly upon the margin of the upper lying parallel to the shoe bottom over an insole for example by through-and-through stitching such as in McKay-sewed or Littleway shoes, and the invention is accordingly herein illustrated in its application to the making of shoes of that character. It is to be understood, however, that in its more general aspects the invention is not thus limited in its applicability.

An object of the invention is to provide an improvement in shoemaking by such treatment of the upper as to dispense with fastenings in the insole in one or more locations where such fastenings have been commonly used heretofore for securing the margin of the upper in lasted position, for example in lasting one or both ends of a shoe where it has been customary heretofore to fasten the upper by lasting tacks clinched on the inner face of the insole. In addition to securing advantages such as follow directly from the omission of tacks or other fastenings, including the smoothness of the inner face of the insole because of the absence of fastenings, it is also an object to improve the quality of the shoemaking, especially in respect to the effectiveness of the lasting and the condition of the shoe bottom preparatory to the laying of the outsole.

With the above and other objects in view, the invention, in one of its aspects, provides a novel method involving such treatment of the marginal portion of the upper under pressure as to cause it to become permanently set in lasted position so that the upper will retain its lasted shape without the need of fastenings in the insole. Since treatment of this character, for its best effect, requires that the pressure be maintained for a longer time than it is practicable or convenient for a shoe to remain in a lasting machine, it is contemplated that, in accordance with the preferred practice, there will be utilized a pressuring or clamping device portable with the shoe and its last while maintaining on the marginal portion of the upper materials the required pressure in a direction heightwise of the last. As herein illustrated, such a device is applied in continuous engagement with the margin of the upper around an end of the shoe bottom over a substantial portion of the width of said margin and is pressed down upon the shoe bottom by the wipers of a lasting machine, the device

being fastened to the last through the insole in such manner as to clamp it down upon the upper under substantially the full pressure applied by the wipers. It is further contemplated that in operating upon an end portion of upper materials including a stiffener or stiffening material such as it is customary to use, for example, in a box toe between the leather upper and the lining, properties of the stiffening material may be availed of to render the treatment applied especially effective, since the stiffening material when hardened or set will assist in holding the margin in lasted position. Moreover, if the stiffening material is of a cementitious character, for example such as it is customary to treat by the application of heat or of a solvent prior to lasting, the pressure applied to the margin of the upper materials in the manner above described will cause the stiffening material to penetrate through the lining and engage the insole over which the margin of the upper is lasted, and thus to act as a cement to secure the margin of the upper materials to the insole while also securing the different layers of the materials together. In operating upon work that does not include stiffening material of the above-mentioned character, or if conditions otherwise render it desirable, as in lasting the heel end of a shoe, cement may be applied to secure the margin of the upper to the insole under the clamping pressure. As herein illustrated, the clamping pressure is confined to that portion of the margin of the upper materials that actually overlies the bottom face of the insole, instead of extending to the extreme edge of the shoe bottom, this being regarded as desirable in order to avoid any tendency to relax the tightness of the lasting by pressure applied in line with that portion of the upper which extends heightwise of the last at the edge of the insole.

In another aspect, the invention provides a novel method involving the use of different treatment in lasting different portions of a shoe, especially in respect to the manner of retaining the upper in lasted position. As herein illustrated the upper along the sides of the shoe between its toe and heel ends is secured in lasted relation to the insole by metallic fastenings which are anchored in the body of the insole without penetrating entirely through it, instead of being clinched on any surface of the insole, in accordance with the disclosure of Letters Patent No. 1,815,295, granted July 21, 1931 upon an application of George Goddu, while at its ends the shoe is lasted in the manner hereinabove de-

55

scribed without the use of fastenings in the insole. There may thus be produced a shoe of the above-mentioned type which is not only free from metallic fastenings clinched on the inner face of the insole along its shank and ball portions, but is also free from lasting fastenings in the insole at one or both of its ends as may be preferred. In addition to its method aspects, the invention thus further presents novelty in shoe construction.

The invention will now be more particularly described by reference to the accompanying drawing and thereafter pointed out in the claims.

In the drawing.

15 Fig. 1 is a perspective view showing a portion of a bed lasting machine of well-known type and illustrating in part the manner of lasting the toe and heel ends of a shoe in accordance with the objects of this invention;

20 Fig. 2 is a similar view showing a clamp member applied to the toe end of the shoe;

Fig. 3 is a vertical section illustrating more in detail how the clamp member is applied to the toe while the shoe is in the lasting machine;

25 Fig. 4 is a perspective view showing the clamp member illustrated in Figs. 2 and 3 and also a screw for securing it in clamping position;

Fig. 5 shows another form of clamp member comprising portions adjustable relatively to each other;

30 Fig. 6 shows the forepart of a shoe as it appears after the clamping pressure on the toe portion of the margin of the upper materials has been removed, a portion of the insole and of the last structure being broken away to show how a metal bushing provided in the last to receive the screw is locked to prevent it from turning;

Fig. 7 is a vertical section through the toe portion of a completed shoe in the production 40 of which the invention has been utilized; and

45 Fig. 8 is a vertical section through a side portion of a lasted shoe of the type illustrated in other figures, showing more clearly how the upper is held in lasted position along its opposite sides between its toe and heel ends.

The drawing illustrates the invention in its application to the manufacture of a shoe of the through-and-through sewed type, in which an outsole *a* (Fig. 7) is secured to an insole *b* by through-and-through stitches *c*, that is, stitches which, at least at the time of the outsole-stitching operation, extend through the insole to the inside of the shoe. They further illustrate in special detail the manner of treatment of the upper materials at the end portions of the shoe, and in some of its aspects the invention is not particularly concerned with the manner in which the upper materials are held in lasted position along the sides of the shoe between its toe and heel end portions. Preferably however, and in accordance with one of the objects in view in the application of the invention to the manufacture of shoes free from clinched metallic fastenings on the greater portion at least of the inner face of the insole, the marginal portion of the upper materials along the sides of the shoe will be secured in lasted position by fastenings anchored in the body of the insole without penetrating entirely through it in accordance with the disclosure of the Goddu patent hereinbefore mentioned, these fastenings comprising, as illustrated, staples *d* the legs of which are anchored by curvature in the body of the insole as illustrated particularly in Fig. 8. The staples, it will be observed, extend into portions of the insole not

weakened by channeling. Figs. 1 and 2 show the shoe mounted on a last *e* with the upper materials fastened to the insole in this manner at the shank and ball portions of the shoe, the sides of the shoe having been thus lasted preparatory to the lasting of the toe and heel ends.

5 The drawing illustrates the lasting of the end portions of the shoe as effected by the aid of a bed lasting machine of a well-known type features of which are disclosed in various United States Letters Patent, including Letters Patent No. 1,284,870, granted on November 12, 1918, upon an application of Matthias Brock. It is, accordingly, unnecessary for an understanding of the invention to describe the construction of that machine in detail. It will be understood that the last with its shoe materials is mounted at its heel end upon a shoe support 10 with the forepart of the last and shoe supported on a toe rest 12 (Fig. 3). For lasting the toe there are provided 10 wipers 14 operated by a hand lever (not shown) to wipe the marginal portion of the upper materials inwardly over the insole. There is also provided a toe band 16 for embracing the shoe about the toe and for clamping the upper materials to 15 the end and side faces of the last at the time when the wipers are operated to wipe the margin of the upper materials over the insole. It will be understood that the toe-lasting means comprising the toe band and the wipers is movable 20 heightwise of the shoe by means of a treadle (not shown), and that the wipers 14 are utilized in this movement to wipe the upper heightwise of the toe before wiping it inwardly over the 25 insole. By the same means the wipers may also 30 be pressed downwardly after they have been moved inwardly over the bottom of the shoe by the hand lever.

After the margin of the upper materials has 35 been wiped inwardly over the bottom face of the insole, as illustrated in Fig. 1, and preferably after the wipers have been withdrawn only to such a position as still to engage the overwiped margin of the upper near the edge of the shoe bottom and thus to hold the margin in its inwardly bent condition there is applied to the shoe for 40 purposes of this invention a clamping device or member shaped, for example, as illustrated in Fig. 4, this member comprising a plate 18 having an edge contour approximating the contour of the 45 edge of the shoe bottom about the toe to adapt it to be positioned over the margin of the upper inside of the edges of the wipers and in close relation to these edges while the wipers are positioned as above described. The plate 18 has an upper- 50 engaging face formed for continuous engagement with the margin of the upper about the toe from one side of the toe to the other side, and as illustrated, formed for continuous engagement with all portions of the margin beneath it. Preferably also, this plate is so formed as to be substantially rigid in directions heightwise of the 55 shoe, so as to apply effective clamping and shaping pressure to the margin of the upper materials when the plate is forced downwardly toward 60 the bottom of the last and is held in clamping position by the means hereinafter described.

For pressing the clamping plate 18 toward the bottom face of the last to bring heavy 65 pressure to bear upon the margin of the upper materials, and for also securing and holding the plate in clamping position after the shoe has been removed from the machine, there is utilized, as herein illustrated, a screw 20 arranged to extend through a slot 22 in the plate 18 and into an 70

interiorly threaded metal bushing 24 secured in the last. It will be understood that the insole 5 is provided with a hole 26 in position to align with the threaded recess in the bushing 24. The screw 5 20 may be inserted, if desired, before the plate 18 is applied over the margin of the upper, as shown in Fig. 1, with the head of the screw upraised far enough to permit the plate to be positioned inside of the edges of the wipers. It will be understood that the slot 22 in the plate permits the plate to be adjusted lengthwise and angularly in relation to the screw to position it in the desired relation to the margin of the upper and the edges of the wipers. After the plate has been 10 15 properly positioned, the screw is turned by the use of a suitable tool to cause its head portion which overlaps the plate to force the plate down toward the bottom face of the last and thereby to bring heavy pressure to bear upon the margin 20 of the upper materials. If desired, after the screw has been turned enough to cause the plate to hold the margin of the upper materials effectively against displacement, the wipers 14 may be raised and advanced over the top of the plate, 25 as illustrated in Fig. 3, and then forced down by the action of their operating treadle to assist in applying the plate to the margin of the upper with the desired pressure, the screw being further turned while the wipers are thus acting so 30 as to maintain the full pressure applied by the wipers. Thereafter the wipers will be retracted, leaving the plate applied to the shoe as illustrated in Fig. 2, and then the shoe will be removed from the machine and put aside until the margin of 35 the upper materials has set in lasted position. It will be evident that the clamp member or plate is thus secured by the screw 20 in clamping relation to the bottom of the last, i. e., so that the plate co-operates with the last in pressing the 40 margin of the upper toward the bottom of the last and in maintaining the pressure, the screw being located farther inwardly from the edge of the shoe bottom than the margin of the upper. It will also be evident that the plate shown extends 45 farther inwardly over the shoe bottom than it may be practicable or desirable to move the wipers, especially if the upper is lasted with cement, so that under all conditions the upper is pressed down as far inwardly as its edge. 50 The toe portion of the shoe herein shown, as illustrated in Fig. 3, includes in its upper materials a leather upper *f*, a lining *g*, and a box toe stiffener *h* inserted between the leather upper and the lining. The stiffener *h* may include in its 55 composition cementitious stiffening material such as it is customary to use in box toes, for example material adapted to be treated by heat or by a solvent prior to lasting. It is contemplated that when such stiffening material is used its cementitious properties may be availed of to render especially effective the pressing treatment applied to the margin of the upper materials as hereinbefore described, since under the pressure the stiffening material will be forced through the 60 65 lining *g* so as to contact with the insole under the lining and thereby act as cement to secure the margin of the upper materials to the insole while also securing the different layers together. If the toe does not include stiffening material of the character described, cement may, if desired, be applied to the margin of the upper materials to cause the different layers to adhere to each other and to the insole under the pressure of the plate 70 75 18. It is considered, however, that under some conditions the use of cementitious material of any character will not be necessary to the accomplishment of the objects of the invention, but that the margin of the upper materials under the continued heavy pressure of the plate 18 will become so effectively set in lasted position that the upper materials will be retained in lasted shape without adherence of the margin to the insole.

After the margin of the upper materials has remained under the clamping pressure of the plate 18 a sufficient time to become set in lasted position, the plate and the screw 20 are removed. Thereafter the outsole *a* is laid on the bottom of the shoe and secured to the insole by the through-and-through stitches c. 10 15 20 25 30 35 40 45 50 55 60 65 70 75

In addition to such advantages as arise from the omission of lasting tacks about the toe, including advantages due to the smoothness of the inner face of the insole as compared with conditions where tacks are clinched on that face and to the absence of any danger of breaking the needle of the outsole-sewing machine by engagement with tacks, there are also other important advantages resulting from treatment such as above described. With pressure applied to the margin of the upper materials continuously throughout the length of the margin under treatment, the upper is held more effectively in lasted position than it is, for example, by tacks inserted at spaced intervals, and this contributes to a more tightly lasted shoe than it is possible to obtain by the use of spaced fastenings. Furthermore, as illustrated the margin of the upper materials is pressed substantially throughout its width so flat upon the insole that there is no need for a later trimming operation such as is necessary where tacks are used, and the bottom of the toe portion of the shoe also is in a flatter and generally more satisfactory condition for the reception of the outsole than it is where the upper is tacked and trimmed. 35 40 45 50 55 60 65 70 75

It will be observed that the clamping plate 18 applied as hereinbefore described is in a position in which its outer edge is spaced from the extreme edge of the shoe bottom, as illustrated in Fig. 3, since the plate is positioned inside of the edges of the wipers when the wipers are holding the upper at the edge of the shoe bottom. To locate the plate in this relation to the shoe is of further advantage by reason of the fact that there is no clamping pressure in line with that portion of the upper which extends heightwise of the last at the edge of the insole, such as might tend to relax the tightness of the lasting along the insole edge. As illustrated, the clamping pressure is confined to that portion of the margin of the upper materials that actually overlies the bottom face of the insole. 55 60 65 70 75

Preferably the metal bushing 24, which extends inwardly from the bottom face of the last, will be exteriorly threaded, as illustrated, to adapt it to be screwed into the last. In order to lock this bushing from turning in response to the turning of the screw 20, the outer end of the bushing is so formed as to have at opposite sides straight edge faces one of which is seen at 28 (Fig. 6), and to co-operate with these edge faces in holding the bushing from turning there is secured on the bottom of the toe end of the last, by means of screws 30, a metal plate 32 having an opening therein to fit the end of the bushing and thus to lock the bushing in place. It will be evident that the plate 32 not only prevents turning of the bushing but also assists in holding it against the pull of the screw 20 thereon. 70 75

If desired, a clamp member of the form shown in Fig. 5 may be used, this member comprising two opposite halves or side portions 34 hinged together by a pivot stud 36 so that the two portions 5 may be adjusted laterally of the shoe for shoes of different sizes. It will be understood that, except for this provision for adjustment, this form of clamp member will be used in all respects in the same way as the member 18 shown in Figs. 2, 3 10 and 4.

While the invention has been described above with particular reference to the lasting of the toe, it is contemplated that, if desired, the heel end of the upper materials will be treated in a 15 similar manner, and such treatment of that portion of the materials is illustrated in Fig. 1. For this purpose there will be utilized a suitably formed clamping plate 38 of the same general character as that hereinbefore described for use 20 at the toe, together with a screw 40 extending through a hole in the heel end of the insole into a threaded bushing in the heel end of the last. If desired, cement may be utilized to cause the 25 margin of the heel end portion of the upper materials to adhere to the insole under the clamping pressure. The heel end may thus be lasted while the shoe is in the bed lasting machine, either before or after the toe end is lasted. Fig. 1 shows a portion of the clamping plate 38 broken 30 away to indicate the condition of the margin of the upper after treatment by the clamping pressure. It will be understood that the heel-clamping plate 38 as well as the toe-clamping plate 18 will remain on the shoe after the shoe has been 35 removed from the lasting machine until the margin of the upper materials has set in its lasted position.

From the foregoing description it will be seen that there is produced by the use of this invention a shoe which is entirely free from lasting fastenings in the insole at one and it may be both of its end portions, and if the upper materials are secured to the insole in the manner herein illustrated in the side lasting of the shoe, the 45 shoe is also free from any lasting fastenings on the inner face of the insole along its opposite side portions. The lasted shoe, moreover, is in such condition that not only is no trimming needed at the toe preparatory to the laying of the outsole, 50 but the bottom face of the toe is in a flatter and generally more satisfactory condition for the reception of the outsole than where it is lasted with tacks and thereafter trimmed. A similarly desirable condition is also present at the heel end 55 of the shoe when that end is subjected to the treatment described.

The novel upper-holding means herein disclosed is claimed in a divisional application, Serial No. 494,152, filed on November 7, 1930.

60 The term "margin" as used herein with reference to the upper materials is intended to designate that portion of the materials which is lasted inwardly over the outer or bottom face of the insole.

65 Having described the invention, what I claim as new and desire to secure by Letters Patent of the United States is:—

1. That improvement in methods of making 70 shoes which consists in lasting the margin of upper materials about an end of a last inwardly over an insole on the last and then holding said margin in an inwardly bent condition by engaging it adjacent to the edge of the shoe bottom, while thus holding the margin of the upper materials 75 applying in continuous engagement therewith

round the end of the shoe bottom from a location substantially over the edge of the insole inwardly a clamping device portable with the shoe and last, pressing the margin of the materials forcibly against the insole in a direction toward the bottom face of the last by said clamping device, securing said device in clamping position by means that presses it toward the bottom of the last and maintaining the pressure thus applied until the margin of the upper materials has substantially set in lasted position, and thereafter releasing the margin from the clamping pressure and proceeding with the manufacture of the shoe. 10

2. That improvement in methods of making 15 shoes which consists in lasting the margin of upper materials about an end of a last inwardly over the bottom face of an insole on the last in substantially parallel relation to the last bottom, then utilizing in continuous engagement with the margin of the upper materials round the end 20 of the shoe bottom a clamping device portable with the shoe and last to press the margin of the materials forcibly upon the bottom face of the insole in a flat condition over at least the greater portion of the width of said margin, securing said device in clamping relation to the bottom of the last after thus utilizing it to press the materials upon the insole and maintaining the pressure thus applied until the margin of the upper 25 materials has substantially set in lasted position, and thereafter releasing the margin from the clamping pressure, applying an outsole over the insole and securing the outsole directly to the margin of the upper. 30

3. That improvement in methods of making 35 shoes which consists in lasting the margin of upper materials about the toe end of a last inwardly over the bottom face of an insole on the last in substantially parallel relation to the last bottom by the use of toe-embracing wipers in a 40 lasting machine, then by the use of said wipers in engagement with the margin of the upper materials adjacent to the edge of the shoe bottom holding said margin in an inwardly bent condition, while the margin is thus held applying in 45 substantially continuous engagement therewith round the end of the shoe bottom inside of the edges of the wipers a clamping device portable with the shoe and last and by the action of said clamping device pressing the margin of the upper 50 materials forcibly against the bottom face of the insole in a flat condition from a location substantially over the edge of the insole inwardly, then securing said device in clamping relation to the bottom of the last and maintaining the pressure thus applied until the margin of the upper 55 materials has substantially set in lasted position, and thereafter releasing the margin from the clamping pressure, applying an outsole over the insole and securing the outsole directly to the 60 margin of the upper. 60

4. That improvement in methods of making 65 shoes having in an end portion of the upper materials an end stiffener of a type adapted to be shaped by lasting pressure, which consists in working the margin of said end portion of the upper materials including the stiffener into lasted position over the bottom of a last, then utilizing in engagement with the margin of the upper materials, at least substantially as far outward as the edge of the insole, a device portable with the shoe and last to press said margin toward the bottom face of the last, then securing said device in clamping position by means that presses it toward the bottom of the last and maintaining 70

the pressure thus applied until the upper materials including the stiffener have substantially set in lasted position, and thereafter releasing the margin from the clamping pressure and proceeding with the manufacture of the shoe.

5. That improvement in methods of making shoes having in the toe end portion of the upper materials a box toe stiffener of a type adapted to be shaped by lasting pressure, which consists in working the margin of said toe portion of the upper materials including the stiffener into lasted position over the bottom face of an insole on a last, in substantially parallel relation to the last bottom, then applying in continuous engagement with the margin of the upper materials round the toe a device portable with the shoe and last and utilizing said device to press said margin flat upon the bottom face of the insole throughout at least the greater portion of the width of said margin, then securing said device in clamping relation to the bottom of the last and maintaining the pressure thus applied until the upper materials including the stiffener have substantially set in lasted position, and thereafter releasing the margin from the clamping pressure, applying an outsole and securing it directly to the margin of the upper.

6. That improvement in methods of making shoes having box toes, which consists in working the margin of the toe end portion of upper materials, including cementitious box toe stiffening material, into lasted position upon an insole on a last, utilizing a clamping device portable with the shoe and last to press the margin of the upper materials upon the insole continuously all around the toe in a direction transverse to the bottom face of the insole at least substantially as far outward as the edge of the insole, then securing said device in clamping position by means that presses it toward the bottom of the last and maintaining the pressure thus applied until the stiffening material has substantially set, and thereafter releasing the margin from the clamping pressure and proceeding with the manufacture of the shoe.

45. 7. That improvement in methods of making shoes having box toes, which consists in working the margin of the toe end portion of upper materials, including cementitious box toe stiffening material, into lasted position upon an insole on a last in substantially parallel relation to the last bottom, applying to the margin of the upper materials a clamping device portable with the shoe and last and by clamping pressure in a direction transverse to the bottom face of the last all around the toe forcing the stiffening material in said margin against that portion of the insole adjacent thereto to cause the upper materials to adhere to the insole, then securing said device to the shoe and maintaining said clamping pressure substantially undiminished until the stiffening material has substantially set, and then releasing the margin from said pressure and proceeding with the manufacture of the shoe.

8. That improvement in methods of making shoes having box toes, which consists in working the margin of the toe end portion of upper materials, including cementitious box toe stiffening material, into lasted position upon the bottom face of an insole on a last in substantially parallel relation to the last bottom, then applying a clamping device portable with the shoe and last to the margin of the upper materials and by the action of said device pressing said margin all around the toe flat upon the bottom face of the insole while forcing the stiffening material in

said margin against the insole to cause the upper materials to adhere to the insole, then securing said clamping device to the shoe and maintaining the clamping pressure until the stiffening material has substantially set, and thereafter releasing the margin from said pressure, applying an outsole and securing it directly to the margin of the upper.

9. That improvement in methods of making shoes having box toes, which consists in working the margin of the toe end portion of upper materials, including cementitious box toe stiffening material, into lasted position upon the bottom face of an insole on a last in substantially parallel relation to the last bottom, applying a clamp portable with the shoe and last in engagement with said margin all around the toe from its inner edge outward substantially as far only as the edge of the insole and pressing said margin flat upon the insole, then securing said clamp in pressure-applying relation to said margin and to the bottom of the last and maintaining the pressure until the stiffening material has substantially set, and thereafter removing the clamp, applying an outsole and securing it directly to the margin of the upper.

10. That improvement in methods of making shoes which consists in lasting the margin of upper materials about an end of a last inwardly over the bottom face of an insole on the last, utilizing in continuous engagement with said margin, only substantially as far outward as the edge of the insole, a clamping device portable with the shoe and last to press said margin upon the bottom face of the insole, then securing said clamping device in clamping position by means that presses it toward the bottom of the last and maintaining the pressure thus applied until said margin has substantially set in lasted position, and thereafter releasing the margin from the clamping pressure and proceeding with the manufacture of the shoe.

11. That improvement in methods of lasting shoes which consists in wiping the margin of upper materials about an end of a last inwardly over an insole on the last by the use of end-embracing wipers in a lasting machine, then applying in engagement with the margin of the upper materials round the end of the shoe bottom a clamping device portable with the shoe and last and by the use of said wipers pressing the clamping device against the margin of the upper materials toward the bottom face of the last, thereafter securing said clamping device in clamping position by means which also presses it toward the bottom of the last, and then removing the shoe from the lasting machine with the clamping device thus secured in clamping position.

12. That improvement in methods of making shoes of the type having an outsole secured directly upon the margin of the upper lying parallel to the shoe bottom over an insole, which consists in securing the margin of upper materials in lasted position on the bottom face of an insole along portions at least of the opposite sides of a shoe by metallic fastenings anchored in the body of the insole without penetrating its inner face, lasting an end portion of the shoe without the use of fastenings in the insole, and thereafter applying an outsole upon the lasted margin of the upper and securing it.

13. That improvement in methods of making shoes of the through-and-through sewed type which consists in securing the margin of upper materials in lasted position on the bottom face

- of an insole along portions at least of the opposite sides of a shoe by metallic fastenings anchored in the body of the insole without penetrating its inner face, working the margin of the upper materials about an end of the shoe into lasted position upon the bottom face of the insole and holding said margin in lasted position under pressure until it has set sufficiently to maintain the end portion of the upper materials in lasted position without the use of fastenings in the insole, and thereafter applying an outsole over the insole and securing it to the insole by through-and-through stitches.
14. That improvement in methods of making shoes of the type having an outsole secured directly upon the margin of the upper lying parallel to the shoe bottom over an insole, which consists in securing the margin of upper materials in lasted position on the bottom face of an insole along portions at least of the opposite sides of a shoe by metallic fastenings anchored in the body of the insole without penetrating its inner face, working the margin of an end portion of the upper materials into lasted position upon the bottom face of the insole and securing the margin in lasted position only by the use of cementitious material, and thereafter applying an outsole upon the lasted margin of the upper and securing it.
15. That improvement in methods of making shoes of the through-and-through sewed type which consists in securing the margin of upper materials in lasted position on the bottom face of an insole along the opposite sides of a shoe by metallic fastenings anchored in the body of the insole without penetrating its inner face, lasting the toe and heel ends of the shoe and holding the margin of the upper materials in those locations in lasted position under pressure until said margin has set sufficiently to remain in lasted position without the use of fastenings in the insole, and thereafter applying an outsole over the insole and securing it to the insole by through-and-through stitches.
16. That improvement in methods of making shoes of the through-and-through sewed type which consists in securing the margin of upper materials in lasted position on the bottom face of an insole along the opposite sides of a shoe by staples curved to anchor them in the body of the insole without penetrating its inner face, working the margin of the toe portion of the upper materials into lasted position on the insole and securing the margin in lasted position only by the use of cementitious material, and thereafter applying an outsole over the insole and securing it to the insole by through-and-through stitches.
17. A shoe having an outsole secured to an insole by through-and-through stitches, said shoe being provided with a plurality of separate lasting fastenings securing the upper permanently to the insole along the shank and ball portions of the shoe and having both its toe and heel end portions free from lasting fastenings in the insole.
18. A shoe having an outsole secured directly upon the margin of the upper lying parallel to the shoe bottom over an insole, said shoe being provided along its sides with metallic lasting fastenings securing the upper to the insole and anchored in the body of the insole without penetrating its inner face and having an end portion thereof free from lasting fastenings in the insole.
19. A shoe having an outsole secured to an insole by through-and-through stitches, said shoe being provided along its shank and ball portions
- with lasting staples securing the upper to the insole with their legs curved to anchor them in the body of the insole without penetrating its inner face and having its toe portion free from lasting fastenings in the insole.
20. A shoe having an outsole secured to an insole by through-and-through stitches, said shoe being provided along its opposite side portions with lasting staples securing the upper to the insole with their legs curved to anchor them in the body of the insole without penetrating its inner face and having the toe and heel end portions of its upper secured to the insole by cementitious material without lasting fastenings in the insole.
21. A lasted shoe of the type in which an outsole is secured directly upon the margin of the upper lying parallel to the shoe bottom over an insole, having its upper along portions at least of the sides of the shoe held in lasted position by permanent metallic lasting fastenings so applied in an unchanneled portion of the insole as not to penetrate to the inner face of the insole and having an end portion of its upper held in lasted position only by cementitious material.
22. A lasted shoe of the through-and-through sewed type having its upper along the sides of the shoe held in lasted position by permanent metallic lasting fastenings so applied as not to penetrate to the inner face of the insole and having the toe portion of its upper held in lasted position prior to the attachment of the outsole only by box toe stiffening material at its margin.
23. A lasted shoe of the through-and-through sewed type having its upper along the shank and ball portions of the shoe held in lasted position by metallic lasting fastenings so applied as not to penetrate to the inner face of the insole and having both the toe and heel end portions of its upper held in lasted position prior to the attachment of the outsole only by cementitious material.
24. A lasted shoe of the type in which an outsole is secured directly upon the margin of the upper lying parallel to the shoe bottom over an insole, having its upper along the shank portion of the shoe held in lasted position by lasting staples curved to anchor them in the body of the insole without penetrating the inner face of the insole and having an end portion of its upper held in lasted position only by cementitious material.
25. That improvement in methods of making shoes which consists in wiping the margin of an upper about an end of a last inwardly over an insole on the last into substantially parallel relation to the bottom of the last by the use of end-embracing wipers of a lasting machine, applying over the end portion of the shoe bottom a clamping device portable with the shoe and last and by use of the wipers pressing said device upon the upper in a direction toward the bottom face of the last, fastening said clamping device under the pressure of the wipers in such manner as to prevent any substantial pressure-relaxing movement of any portion of the device heightwise of the shoe, removing the shoe from the lasting machine with the clamping device thus attached thereto, and at a later stage in the manufacture of the shoe removing said device from the shoe.
26. That improvement in methods of making shoes of the type in which the margin of the toe portion of the upper is fastened by cement in parallel relation to the last bottom upon the outer face of an insole, which consists in wiping

- the margin of the toe portion of the upper inwardly into that relation to the insole upon a last by the use of toe-embracing wipers of a lasting machine and also by use of the wipers 5
- pressing upon said margin in a direction toward the bottom face of the last a clamping device portable with the shoe and last, fastening said clamping device under the pressure of the wipers in such manner as to prevent any substantial 10
- 10 pressure-relaxing movement of any portion of the device heightwise of the shoe, removing the shoe from the lasting machine with the clamping device thus attached thereto, and after the cement has substantially set removing said device from 15
- 15 the shoe.
27. That improvement in methods of fastening the margin of the toe portion of an upper in lasted position over an insole on a last in substantially parallel relation to the bottom of the 20
- 20 last which consists in pressing upon the margin of the upper in that relation to the last in a direction toward the bottom face of the last a clamping device portable with the shoe and last, and while holding said clamping device thus under pressure fastening it to the last through the insole in such manner as to prevent any substantial pressure-relaxing movement of any portion of the device heightwise of the shoe when 25
- 25 the pressure thereon is removed.
- 30 28. That improvement in methods of making shoes which consists in wiping the marginal portion of an upper about an end of a last inwardly over an insole into substantially parallel relation to the bottom of the last by the use of wipers, 30
- 30 thereafter applying a pressing member over the end portion of the shoe bottom and pressing said member upon the upper in a direction substantially perpendicular to the shoe bottom by the wipers, maintaining said member in pressure- 35
- 35 applying relation to the upper until after the upper has substantially set in lasted position, and then releasing the upper from the pressure of said member.
29. That improvement in methods of making 40
- 45 shoes in which an end portion of the upper is secured in lasted position by cement, which consists in wiping the marginal portion of the upper about an end of a last inwardly over an insole into substantially parallel relation to the bottom 45
- 50 of the last by the use of wipers, thereafter applying a pressing member over the end portion of the shoe bottom and pressing said member upon the upper in a direction heightwise of the shoe by the wipers, maintaining said member in position to 55
- 55 hold the upper under substantially the full pressure thus applied until after the cement has substantially set, and then releasing the upper from the pressure of said member.
30. That improvement in methods of making 60
- 60 shoes in which an end portion of the upper is secured in lasted position by cement, which consists in wiping the marginal portion of the upper about an end of a last inwardly over an insole into substantially parallel relation to the bottom of the 65
- 65 last by the use of wipers, thereafter applying over the end portion of the shoe bottom a pressing member extending farther inwardly from the edge of the shoe bottom than the wipers and pressing said member upon the upper in a direction heightwise of the shoe by the wipers, main- 70
- taining said member in pressure-applying relation to the upper until after the cement has substantially set, and then releasing the upper from the pressure of said member. 5
31. That improvement in methods of making 10
- shoes which consists in wiping the marginal portion of an upper about an end of a last inwardly over an insole into substantially parallel relation to the bottom of the last by the use of wipers, thereafter applying over the end portion of the shoe bottom a pressing member extending farther inwardly over the shoe bottom than the wipers and farther inwardly than the edge of the upper and pressing said member upon the upper in a direction heightwise of the shoe by the wipers, 15
- 15 maintaining said member in pressure-applying relation to the upper until after the upper has substantially set in lasted position, and then releasing the upper from the pressure of said member. 20
32. That improvement in methods of making 25
- shoes which consists in lasting the marginal portion of an upper about an end of a last inwardly over an insole on the last, applying a pressing member over the end portion of the shoe bottom and pressing it upon the marginal portion of the upper in a direction heightwise of the last, then fastening said member to the last through the insole by means so applied as to maintain clamping pressure upon that face of the member which is on the opposite side thereof from the bottom 30
- 30 of the last, and after the upper has substantially set in lasted position removing said member from the shoe. 35
33. That improvement in methods of making 40
- shoes which consists in lasting the marginal portion of an upper about an end of a last inwardly over an insole on the last, applying a clamping device over the upper on the end portion of the shoe bottom, fastening said device to the last through the insole farther inwardly from the edge of the shoe bottom than the marginal portion of the upper and in such manner as to hold it pressed against the upper in a direction toward the bottom of the last, and after the upper has substantially set in lasted position removing said device from the shoe. 45
34. That improvement in methods of holding 50
- the marginal portion of an upper in lasted position over an insole on a last which consists in applying over the marginal portion of the upper an upper-holding device, substantially rigid against bending strains heightwise of the last, and fastening said device to the last through the insole farther inwardly from the edge of the shoe bottom than that portion of the device that engages the upper. 55
35. That improvement in methods of holding 60
- the margin of an end portion of an upper in lasted position over an insole on a last which consists in applying over the margin of the upper an upper-holding device engaging the margin from the inner edge thereof substantially as far outward as the edge of the insole in all locations around the end of the shoe bottom, and fastening said device to the last through the insole by fastening means applied in clamping relation to that face of the device which is on the opposite side thereof from the bottom of the last. 65
